CLAIM

The ornamental design for a weight applying machine for installing a veneer floor surface, substantially as shown.

DESCRIPTION

FIG. 1 is a side elevational view of a weight applying machine for installing a veneer floor surface showing our new design.

FIG. 2 is a top plan view thereof.

FIG. 3 is a rear elevational view thereof.

FIG. 4 is a front elevational view thereof.

FIG. 5 is a side perspective view thereof opposite from the side view shown in FIG. 1.
